UNITED STATES PATENT OFFICE.

FREDERICK BAKER, OF BLACKHEATH, ENGLAND, ASSIGNOR TO BAKER SEWING MACHINE TRUST, LIMITED, OF LONDON, ENGLAND.

SEWING-MACHINE.

1,238,979.

Specification of Letters Patent.

Patented Sept. 4, 1917.

Application filed June 20, 1913. Serial No. 774,801.

To all whom it may concern:

Be it known that I, FREDERICK BAKER, a subject of the King of Great Britain, residing at 42 Lee road, Blackheath, in the 5 county of Kent, England, have invented certain new and useful Improvements in and Relating to Sewing-Machines, of which the following is a specification.

This invention relates to sewing machines 10 and has particular reference to machines of the kind in which an angularly movable loop drawing device situated below the needle plate engages the needle thread at each descent of the needle and after pulling 15 out a loop of thread becomes disengaged from the same before the bight has been carried through a semi-circle. A machine working on this principle of early release of the loops is provided with a stationary 20 casing, which is situated adjacent to the loop drawing device and contains a loop arresting and retaining element in the case of producing single thread stitching, as disclosed in United States Patents No. 1014033 25 and No. 1072201, or a spool of thread in the case of producing double-thread lock stitching, as disclosed in United States Patent 1047728. In the case of producing single-thread lock stitching the casing and 30 its loop arresting and retaining element may be termed a tension device since it arrests certain loops and yieldingly retains them in tension while others are allowed to pass freely over the device.

35 One of the objects of the present invention is to provide a form of tension device of greater precision and certainty of action than the type of device hitherto employed, and in particular to provide for a rotary 40 motion of the loop arresting and retaining hook, or to so modify this element that it cannot catch any loop except that which it is intended to catch and ultimately enables the bight of a rightly caught loop to 45 become disengaged without necessitating an actual unhooking action. A further object is to alter the position of the stationary casing, so as to improve the manner in which the loops are made to pass around 50 and over it, and reduce the extent of the movements required in manipulating the loops generally. Improvements in these and other directions as hereinafter explained result in simplification of parts, im-

proved timing and adjustment, and a su- 55 perior quality of sewing.

According to one feature of the present invention the loop arresting and retaining element of the tension device for single thread stitching performs its functions by 60 a rotary motion. A convenient form of the said element comprises a circular plate rotatably mounted within the casing of the device, and a number of hooks or equivalent 65 loop arresting elements formed or carried on or near the periphery of the plate, as hereinafter more fully explained.

In a modified form of the tension device the loop arresting and retaining element, after arresting a loop, loses its loop-arresting property but preserves its loop-retaining property until it has moved into its loop-delivering position, whereupon it also loses its loop-retaining property. A convenient form of loop arresting and retaining 70 element of this kind is one of an oscillatory character comprising two members, one of which serves, at the correct intervals, to shroud the other member so as to render it incapable of wrongly catching a loop and 75 also serves to retain a rightly caught loop and prevent it from escaping prematurely. The one member closes upon the other, preventing premature escape of an arrested loop and shrouding the loop arresting member, 80 and subsequently the members open, thereby 85 freely releasing the loop.

The above mentioned stationary casing either contains a spool or bobbin, or a loop arresting and retaining element, as hereinbefore stated. In either case it has been found advantageous to locate the said stationary casing laterally with respect to one face of the loop drawing disk. The said casing may be kept in contact with the 90 loop drawing disk by intermittently retracted prongs, or by a roller, or by a laterally projecting member on a rotating plate engaging in a corresponding groove on the rear face of the casing, as hereinafter 95 described. The intermittent retraction of the prongs or the speed of rotation of the plate is such that the passage of the thread over the corresponding face of the stationary casing is not hindered and may in fact be 100 assisted.

The above stated lateral positioning of the stationary casing enables a new principle of

manipulation of the thread to be adopted as will now be explained. It will be understood that in this case the needle at each descent passes down between or alongside the sliding surfaces of the stationary casing and the loop-drawing disk; means are therefore provided whereby each loop of thread formed at the commencement of each ascent of the needle is turned over by the engaging of its bulging strand and the drawing-out of it across the inner face of the casing, whereupon it becomes free to be drawn up over the outer face of the casing, a part of the loop having meanwhile been slidably detained near the path of the needle. In order that the loops of thread may be drawn out in this way, one or more loop engaging elements projecting from the face of the disk may be provided, a recess or number of recesses in the adjacent face of the casing being formed to permit these elements to pass within and along the same. A convenient form of projecting element, and one which also assists in keeping the casing in its correct position against the face of the disk, is a laterally projecting tongue with a gap in it, the part with which the tongue engages on the adjacent face of the casing comprising an arc-shaped groove. In this way the casing may be kept quite near to the rear face of the disk, the said tongue sliding in the groove as the disk rotates. The disk and casing are so situated relatively to the needle that as the latter descends it passes down near the face of the disk. In order that the needle may make this descent and form a loop, a portion of the tongue is cut away and a portion of the disk may be cut away as well; the timing of the parts is of course such that the gap in the circular tongue registers with the path of the needle at the time when the needle is in the act of ascending. A notch or catch on the casing near the path of descent of the needle serves to catch and retain a part of the loop while the bulging strand is being manipulated. As the disk rotates the tongue advances with it and a loop of thread is drawn out. Immediately the advancing end of the tongue passes away out of engagement with the groove on the casing the loop becomes free and is then in such a position that, when it is being drawn up, one strand of the loop will glide over the outer face of the casing. In order that the invention may be clearly understood and readily carried into effect the same will now be described more fully with reference to the accompanying drawings in which:—

Figures 1 to 4 illustrate diagrammatically the new principle of drawing out loops of thread as hereinbefore mentioned; Figs. 1 and 2 show a tension device situated laterally with respect to the loop drawing disk (shown in dot and dash lines) and two posi-

tions of a loop in the course of encircling the device; Figs. 3 and 4 show the device enlarged and the thread in two other positions.

Fig. 5 is a longitudinal sectional elevation, Fig. 6 an end elevation, and Fig. 7 a plan, of parts of a machine operating on the new principle referred to. It will be understood that Fig. 6 is an elevation as viewed from the front end of the machine, that is to say as viewed from the right hand end of Fig. 5.

Fig. 8 is a view of the rear face of the loop drawing disk and Fig. 9 corresponds with Fig. 6 with the exception that the disk is removed.

Fig. 10 is a detail view of part of the mechanism shown in Figs. 5, 7 and 9.

Figs. 11 to 17 relate to the construction of the tension device used with the disk and other machine parts shown in Figs. 5 to 10. This tension device presents slight modifications as compared with that shown in Figs. 3 and 4.

Fig. 18 shows diagrammatically the function of a lip on the disk for controlling the position of the strand of a loop when being drawn out, as hereinafter described.

Fig. 19 is a side elevation and Fig. 20 an end view of parts of a modified machine in which the conveying of the loops past the outer face of the tension device, and the keeping of the latter in position, are performed by a continuously rotating plate; Fig. 21 is a view of the back face of the loop drawing disk; Figs. 22 and 23 show in end elevation and in two different positions the driving mechanism for the disk and plate, and Fig. 24 is a side elevation corresponding to Fig. 23; Fig. 25 is a view of the outer face of the tension device by itself.

Figs. 26 and 26^a illustrate one form of intermittently actuated prong mechanism to keep the tension device in its lateral position against the loop-drawing disk.

Figs. 27, 27^a, 27^b, 27^c and 28, illustrate the internal mechanism of a tension device of the finger-shrouded type hereinbefore referred to, Fig. 27 being a side elevation and Fig. 28 an end elevation of the device with its cover plate removed. Fig. 29 illustrates a lever and means for operating it, the said lever being required to actuate parts of the tension device of Fig. 27. Fig. 29^a is similar to Fig. 29 but the loop drawing disk is removed, exposing the tension device and other parts behind it.

Figs. 30, 31 and 32 illustrate a modified form of the finger-shrouded type of tension device, Fig. 30 being an external view, and Figs. 31 and 32 two internal views.

Referring now to the diagrammatic Figs. 1 to 4, and the corresponding machine parts shown in Figs. 5 to 10, it may be noted in the first place that the rotary disk B rotates

counter clockwise as viewed from the front end of the machine. Viewing the parts from the front end of the machine, the vertical diameter of the loop arresting plate d within 5 the casing D of the tension device appears in the same vertical line as the path of the needle; the part of the casing on the right hand of the path of the needle is approximately semi-cylindrical and the remaining 10 part and also including its tail portion extends downwardly toward the left, the tip of the tail being practically on the path of a circular tongue B' with a gap in it, the tongue being formed laterally on the disk 15 and sliding in a groove in the tension device casing. The needle descends in a cut-away portion D^o (Fig. 7) of the casing against the vertical diameter of the loop arresting plate and between it and the gap 20 in the tongue B' on the disk, and the groove D^s in the casing extends from a point just to the left of the needle to the tip of the tail portion. When the needle A is down and presenting a loop of the thread C . The 25 advancing end of the tongue B' on the disk catches the bulging strand and immediately afterward enters the groove D^s in the casing, the result being that the strand becomes trapped and drawn along across the inner 30 face of the casing as shown in Fig. 1, and is unable to escape until the advancing end of the tongue passes out of the groove at the tail of the casing, whereupon the bight of the loop becomes released from the tongue 35 and moves in a direction away from the disk and toward the outer face of the casing, as shown in Fig. 2. The size and position of the casing D relatively to the disk B are preferably such that the bight of each loop 40 of needle thread need not be drawn out through more than about ninety degrees or at most about one hundred and twenty degrees of angular movement.

In order to keep one part of the strand 45 of each loop in place while the bulging part is being caught, and drawn across the inner face of the casing, released, and then drawn back across the outer face of the casing, a catch D^{ss} is formed or provided on or near 50 the lower corner of the groove D^s in the casing at the entering end of the groove, the said catch being adapted to arrest and retain one part of the loop as shown in Figs. 1 and 2, while the other part is being manipulated as described. After the manipulated part of the loop, in passing back across 55 the outer face of the casing, has come into vertical alinement with the retained part, the two parts or strands, constituting the 60 loop, pass up over the semi-cylindrical right hand part of the casing as shown in Fig. 3. In the case of single thread lock-stitching the loop in passing up over the said right hand portion of the casing is arrested or not 65 by a projecting hook d^s on the circular loop

arresting plate d according as a hook is in position (Fig. 3) or not (Fig. 4). If a hook is in position the rear thread of the arrested loop slips over the curved wall of the casing into the space immediately behind the loop arresting plate, the other strand extending of course immediately across the front face of the plate as seen in Fig. 4. In this way lock stitching of the kind disclosed in the specification of the 70 prior United States Patent No. 1072201 is produced. If it is desired to produce the type of stitching in which each sub-loop merely embraces the main loop without being embraced by it, each main loop while 75 being retained in tension is so controlled that the needle in descending for each sub-loop passes down at one side of the retained main loop. If on the other hand it is desired that each sub-loop should not only embrace the 80 main loop but be embraced by it, the main loop is kept slightly expanded so that the needle at each descent for the formation of a sub-loop passes through the retained main 85 loop.

The bight of every loop that is arrested by one of the hooks is drawn toward the hole in the needle plate by the action of the take-up or of the feed mechanism that advances the material stitch by stitch. This 90 forward movement of the loop causes the plate to turn upon its axis and the rotation of the plate ultimately presents the bight quite close up to the hole in the needle plate. Another loop is then drawn from the 95 needle, and it is necessary for the bight of the old loop to be then set free. This release of the bight of the old loop may be effected automatically by the mere turning effect upon the rotary plate of the next 100 main loop as the latter is being formed on the next hook, or by the feed movement. The actual presentation of the bight to the 105 needle at the instant when the needle descends to pierce the bight will be referred to 110 later.

In this machine the means for keeping the tension device casing in position against the face of the disk comprise an oscillatory segment F adapted to work in a depression or 115 track D^s formed to receive it on the rear face of the casing, as shown clearly in Figs. 10 and 17. This segment forms part of a sleeve F' which is rotatably mounted in a bracket and is also formed with a toothed 120 segment F^s . The plane of the segment F is at about forty-five degrees to the horizontal, and its periphery has a small axially disposed groove F^s cut in it for the purpose hereinafter described. A toothed segment 125 G pivoted to the frame of the machine, or to a bracket thereon, engages with the toothed segment F^s of the sleeve F' and is intermittently oscillated by the engagement with a slot g (Fig. 10) in the said segment 130

of a pin or roller g' carried on one end of a rod G' (Figs. 5 and 7) the other end of which carries a roller G^2 working in a cam groove G^3 formed in a collar G^4 on the main shaft. The operation of these parts is as follows:—When the strand of a loop is being drawn up over the outer or rear face of the tension device casing, the cam groove G^3 operates the rod G' which oscillates the toothed segment G , which in turn oscillates the toothed segment F^2 and thereby causes the segment F to turn. At the instant when the strand arrives at the position where it has to pass between the segment F and the outer face of the casing, the axially disposed groove F^3 in the segment F is in a position to coincide with the strand, with the result that the strand, instead of being pinched between the segment and the casing, is housed in the groove F^3 and is "wiped" forward by the angular motion of the segment. When the strand is delivered free on the other side of the track D^x , this segment (F) is returned to its normal position by the retraction of the rod G' due to the action of the cam groove G^3 . Owing to the fact that the outer face of the casing is recessed at D^x , with the segment F working in the recess or track, the tension device is kept in position against the face of the disk B , but in order that the friction between the disk and the inner face of the casing may not cause the casing to slip angularly, a stop may be provided to butt up against the tail portion of the casing. Such a stop is shown in Figs. 5 and 7, it being constituted by one wing H of a two winged sleeve H' , the other wing H^2 of which is attached to one end of a spring H^3 , which keeps the wing H normally pressed against the tail end of the tension device casing. The wing H^2 is however intermittently tapped in order momentarily to move the wing H away from the casing at the instant when loops pass over the tail of the casing. This tapping of the wing is effected by the end of the rod G' ; the movement required to be imparted to the wing H is much less than that performed by the rod G' and the wing is therefore so placed that the rod engages with it only for a fraction of the total movement of the rod.

In order that the strand of a loop when being drawn out may not slip between the tension device casing and the disk, the loop is expanded by providing on the disk a lateral circular lip B^2 at its periphery. This lip, which extends around the greater portion of the periphery as seen clearly in Fig. 8, rides upon a curved ledge B^{2x} (Fig. 13) on the adjacent face of the tension device casing and the strand necessarily passes from the bight up through the gap in the disk (Fig. 18) and lies on the outer curved surface of the lip or of the casing, which

two surfaces act as though they were one unbroken surface.

In case the bight of a loop, when released, should adhere to the disk, a "wiper" in the form of a segmental strip of metal K , shown in Fig. 9, is carried by a bracket K' and is situated to lie in a circular groove B^3 formed at the base of the channel between the tongue B' and lip B^2 of the disk B . This wiper is situated near the tail of the tension device casing as shown in Figs. 6 and 9. Fig. 9 also shows clearly a cam K^2 for operating the feed plate K^3 in a manner well understood. In this figure (Fig. 9) is also seen a guide K^4 to direct the bight of each main loop toward the point at which the loop is resting plate of the device is exposed.

More specific reference will now be made to the construction of the tension device illustrated as being used with this machine. The device comprises the casing proper D and a cover piece screwed thereon. The segmental groove D^3 is formed on the face of the cover piece and the catch D^{3x} is formed on the lower edge of the groove at its forward end. The external surface of the cover piece on the lower side of the groove is slightly receding so that the strand of a loop when caught on the catch D^{3x} and being drawn out toward the tail of the casing is not nipped between the surface of the cover piece and the adjacent surface of the disk.

To enable the internal mechanism of the device to be placed in position the casing is suitably recessed as shown in Fig. 11. The loop arresting plate d (Fig. 15) has a central hole in it to enable it to fit upon an annular hub d^{14} (Fig. 11). The locking lever d^{12} engages with notches d^x on the loop arresting plate at intervals and is released therefrom by the engagement of the cam d^{13x} on the disk (Fig. 8) with the nose d^{12x} on the locking lever. The loop arresting plate is locked during the periods when a main loop is caught by a hook on the plate and is being formed on the hook by the action of the take-up. The plate is then released as above described and is able to turn step-by-step as the loop is drawn forward stitch by stitch by the feeding mechanism. Suitable means, however, are provided to restrain or control the freedom of the plate in its rotation. Such means may, for instance, consist of a small flat spring d^{xx} , housed in the inner face of the cover piece, as shown in Fig. 14, and bearing against the adjacent face of the loop arresting plate d to exert a restraint upon the movements of the plate. Each hook on the plate is presented at one period in the path of the loops and afterward becomes housed under the curved wall of the casing, as will be readily understood. The bight of each arrested loop is finally delivered or escapes from the hook. It will

110
115
120
125

be understood that if the hooks on the arresting plate are actually in the plane of the plate, as shown in Figs. 12 and 15, they cannot present a bight centrally to the needle 5 since the latter in its ascent and descent has to pass at one side of the plate; consequently, means, such as a horn J, must be provided, in order to keep the loop open and eventually present the bight centrally to the needle so that the latter may pierce it. The horn J illustrated in Figs. 12 and 13 is formed on a segmental plate J' (Fig. 16) having a center pin J² which fits into a hole in a boss d¹⁵ projecting centrally within 10 the annular hub d¹⁴ of the tension device casing. A small spring coiled within the annular space between the hub d¹⁴ and the boss d¹⁵ engages with a stop J³ on the underside of the segmental plate J'. The 15 coiled spring keeps the horn J and plate J' in a normally lowered position, the horn pointing at an angle of about thirty-five degrees to the vertical. The edge J⁴ of the plate J' bears against a ledge J^{4x} (Fig. 14) 20 on the inner face of the cover piece of the device to limit the downward angular movement of the horn. When a loop is caught by a hook on the loop arresting plate and this plate moves forward angularly, the 25 bight of the loop embraces not only the hook but also the horn, and when the hook reaches the horn these two parts move angularly together until the horn is nearly vertical, that is to say nearly in line with the path of the 30 needle. The bight is then in a truly central and appropriately expanded condition, so that, when the needle descends, it cannot fail to penetrate the bight. As soon as the bight escapes, the plate J', carrying the horn with 35 it, springs back to its normal position.

In contrast with this movable horn, the horn of the device shown in Figs. 3 and 4 is stationary, being integral with the cover piece of the tension device casing.

40 A modification of the rotary type of mechanism for keeping the tension device in position and in some respects an improvement upon the mechanism described with reference to Figs. 5 to 10 is illustrated in Figs. 19 to 24 and will now be described. In this case the function of the oscillatory segment of the machine shown in Figs. 5 to 10 is performed by the plate L mounted in a plane parallel with the plane of the loop 45 drawing disk B, and formed with a laterally projecting flange l^x adapted to slide in a corresponding segmental groove l^o (Fig. 25) on the outer face of the tension device casing. The flange l^x (which has a gap in it) and groove l^o serve efficiently to keep the tension device in position, and the gap between the ends of the flange allows the thread to pass between the plate L and the casing of the device without becoming 50 pinched between them, just as the groove

on the segment F of Fig. 10 prevented pinching of the thread. The plate L is mounted upon a spindle L', the rotation of which is properly timed relatively to the rotation of the main shaft. The said spindle 70 is conveniently driven from the same source of power as that which drives the main shaft; such an arrangement is shown in Figs. 22 to 24 where L² represents a crank on the usual top or power shaft of the machine and L³ represents a slotted connecting rod connected at one end with the crank and at the other end with a short link L⁴ pivoted to a driving disk L⁵ mounted on the rear end of the main shaft of the machine. A 75 pivoted block L⁶ works in the slot in the connecting rod L³ and provides the connecting rod with the necessary center of oscillation in the known manner. The connecting rod is slightly shorter than the distance 80 between the axes of the top and bottom shafts with the result that the bottom or main shaft has an accelerated motion during part of each revolution, as is well understood. An arm L⁷ on the connecting rod 85 is pivotally connected to a diametrically mounted bar L⁸ slidably dove-tailed onto the face of a disk L⁹ which disk is mounted on the rear end of the spindle L', the front end of which carries the flanged plate L. Hence 90 the main shaft and the spindle will be driven together at substantially the same rate from the top shaft by a single connecting rod, namely the slotted rod L³.

In the two constructions shown in Figs. 100 1 to 18 and 19 to 25 respectively, the tension device casing is kept in position against the rear face of the loop drawing disk by means of an oscillatory segment, or a flanged rotary plate. The tension device might however be 105 kept in position otherwise, as for instance by means of prongs intermittently retracted at certain intervals to allow the loops to pass across the rear face of the casing. One form of such prong mechanism is illustrated in 110 Figs. 26 and 26'. A bracket O supported by some stationary part of the machine carries two spring-controlled prongs M and N which are shaped at the front ends to engage in corresponding recesses in the rear 115 face of the tension device casing D and carry at their rear ends balls M' N' respectively bearing against a plate P having cam shaped recesses m and n on its face in a position such that, as the plate rotates, the 120 ball M' at the rear end of the prong M travels in the recess m, and the ball N' at the rear end of the prong N travels in the recess n. The plate P normally keeps the balls M' and N' and hence also the prongs 125 M and N thrust toward the rear face of the tension device casing but the recesses m and n allow the controlling springs M² N² of the prongs to retract the latter at the correct instants to allow the thread of the loops 130

when being drawn up to pass between the front ends of the prongs and the rear face of the casing.

Reference will now be made to the forms 5 of tension device in which the loop arresting element consists of two members one of which shrouds the other at certain intervals.

In the construction shown in Figs 27, 27^a, 27^b, and 28 the loop arresting element 10 consists of a member Q which is rotatably mounted in a cylindrical recess in the tension device casing D and is provided with a loop arresting finger q and a tail piece q', and a member R which is pivoted at r upon 15 the tail piece q'. The member R consists of the tail piece r' which approximately coincides in shape with the tail piece q', and the shrouding arm r². A spring S attached at one end to the casing D and at the 20 other end to a point on the shrouding arm r² of the member R tends to keep the end of the shrouding arm r² in contact with the end of the finger q, and also tends to keep both members in such a position that the 25 ends of their tail pieces q' r' lie in a hole S° in the curved wall of the casing. A lever S' pivoted at s (Fig. 29^a) to a stationary part of the machine is connected to or formed integrally with an arm s' terminating in a 30 pin s² working in a cam groove s³ on the looping drawing disk. The other end of the arm S' is specially shaped; one half of it is tapered as seen at s° in Figs. 27^a and 27^c, so that, when the lever S' is oscillated by the 35 cam groove s³ and pin s², this tapered end glides under the end of the tail piece q' and holds the member Q firmly; the other half is wedge-shaped as seen at s² in Figs. 27^b and 27^c so that, when the lever S' is oscillated, this wedge-shaped end, in passing under the end of the tail piece r', forces this tail piece upward and thereby causes the end of the shrouding arm r² to move away from the end of the finger q. The operation 40 is as follows:—Prior to the instant at which a loop of thread is to be caught by the finger q, the specially shaped end of the lever S' enters the hole S° of the casing, and thereby locks the member Q in position and tilts the 45 member R sufficiently to ensheathe the finger q. This finger then catches the loop as the latter is being drawn up over the casing; when the loop has been fully drawn out upon the finger q, the lever S' moves back to its normal position, thereby allowing the shrouding arm r² to again engage with the end of the finger piece q. The two members then move forward stitch by stitch in opposition to the tension of the spring S and the loop 50 or loops that are not intended to be caught by the finger are guided over the end thereof by the shrouding arm r², as will be understood from Fig. 27. When the end of the finger q arrives almost vertically under the 55 hole in the needle plate, the tail piece q'

moves beyond a notch q² on a pivoted pawl q³ and is thereby prevented from returning until released, and the tail piece r' of the member R projects into a hole S^x in the casing. A spring controlled cam S^{xx} pivoted 70 at s^{xx} on the driving shaft then passes into the hole S^x in the casing and engages with the tail piece r' and thereby tilts the member R, with the result that the shrouding arm r² moves away from the finger piece q 75 and allows the bight of the retained loop to slip off, and the said cam almost immediately afterward engages a toe q⁴ on the arm q³, thereby thrusting it backward against a controlling spring q⁵ and releasing the tail 80 piece q'. The spring S then returns both members to their lowered position.

Figs. 30, 31 and 32 illustrate a modified form of tension device of the shrouded finger type. In this form of the device the finger 85 q is constituted by an upward and outward projection from a disk q^x rotatably mounted in a cylindrical recess in the tension device casing. The disk q^x is controlled by an underlying coil spring q^{xx} so as to normally 90 assume the position shown in Fig. 31. The shrouding arm r² is constituted by a projection on a disk r^x rotatably mounted upon and concentrically with respect to the disk q^x as seen in Fig. 32. The disk r^x is controlled 95 by an underlying coil spring r^{xx} which tends to keep the end of the shrouding arm r² in contact with the finger q in order to shroud the latter as already described with reference to Figs. 27 and 28. T is a pawl pivoted 100 at t and provided with a locking tooth t' for engagement with slots t² t^{2x} in the disk q^x. The tooth t' of this pawl T is formed with a raised projection t³ having an inclined surface for engagement with a notch 105 t⁴ on the disk r^x. A spring t⁵ thrusts the pawl T against the disks q^x, r^x, and a tail piece t⁶ on the pawl projects through the casing for engagement with notches or cam-shaped projections t⁶ t⁷ on a rotary hub t⁹. 110 On a pivot t^{xx}, a pawl T' is pivoted, and is formed with a nose t⁸ for engagement with a notch t^{4x} on the disk r^x. The operation is as follows:—the disk q^x is normally locked by the tooth t', and the disk r^x is normally 115 turned backward in opposition to its spring by the thrust of the incline on the projection t³ against the notch t⁴, thereby causing the shrouding arm r² to be retracted slightly relatively to the finger q. A loop is therefore caught and drawn out upon the finger q, and the projection t⁶ on the hub t⁹ then engages a tail piece t⁶ of the pawl T and thereby turns the pawl about its pivot t in a clockwise direction to such an extent that 120 the tooth t' becomes withdrawn from the slot t², thereby allowing the finger to advance slightly; the same clockwise motion of the pawl T causes the projection t³ to become 125 withdrawn from engagement with the notch t⁴. 130

t^4 and thus allows the disk r^x to turn and place the shrouding arm r^2 into its shrouding position relatively to the finger g . The disk g^x then yields stitch by stitch and is followed up by the disk r^x . When the finger g is in a practically vertical position under the hole in the needle plate the tooth t' on the pawl T engages in the slot t^{2x} and again locks the disk g^x and a projection t^8 on the hub t^9 thrusts the pawl T slightly upward thus causing the projection t^{1x} on this pawl to press against the notch t^{4x} on disk r^x and turn this disk slightly backward, thereby enabling the bight of the loop on the finger g to escape. The cam shaped projection t^7 then engages with the tail piece t^6 on the pawl T and rocks the same thereby unlocking the disk g^x which immediately flies back to its lowered or normal position, thrusting back the disk r^x with it.

What I claim and desire to secure by Letters Patent of the United States is:—

1. In a sewing machine, the combination with an angularly movable loop-drawing device operating to draw out successive loops from the needle thread but allow each loop to be released before its bight has been carried through two right angles of angular movement, of a stationary casing situated laterally with respect to one face of the loop-drawing device, and coöperating means on said casing and loop-drawing device adapted to cause the bight of the loop to pass across the adjacent lateral face of the stationary casing and to be released at the tail of said casing.
2. In a sewing machine, the combination with angularly movable loop drawing means operating to draw out successive loops from the needle thread but allow each loop to be released before its bight has been carried through two right angles of angular movement, of a stationary tension device laterally situated with respect to one face of the plane of movement of the loop drawing means and comprising a casing around and over which the loops pass in being drawn up, and means within the casing for temporarily arresting certain loops while allowing others to pass.
3. In a sewing machine, the combination with an angularly movable loop-drawing device, of a tension device comprising a stationary casing laterally situated with respect to one face of the loop-drawing device, and coöperating parts upon the adjacent lateral faces of the loop-drawing device and the casing adapted to cause the bulging strand of a loop presented by the needle at the commencement of each ascent, to be trapped and the bight of a loop to be drawn out between the said adjacent lateral faces and released at the tail of the stationary casing in a way that permits of the loop being drawn up around and over the same.
4. In a sewing machine, the combination

of an angularly movable disk, a tension device comprising a stationary casing located laterally with respect to one face of the disk, and interengaging means adapted to cause the bight of successive loops to pass between the adjacent lateral faces of the disk and the casing and each loop to be released before its bight has been carried through two right angles of angular movement and in a position from which when drawn up it will pass around the casing.

5. In a sewing machine, the combination of an angularly movable disk, a stationary casing located laterally with respect to one face of the disk, and tongue and groove inter-engaging parts on the adjacent faces of the disk and the casing operating to entrap the bulging strand presented by the needle at the commencement of each ascent and draw out the bight of a loop between the aforesaid adjacent lateral faces and release the same before its bight has been carried through two right angles of angular movement.

6. In a sewing machine, the combination of a rotatable disk, a stationary casing in slidable contact with the rear face of the disk, a loop-engaging element on the rear face of the disk, means on the front face of the casing for coöperation with the loop engaging element to entrap and draw out successive loops between the sliding surfaces of the disk and the casing and to release each loop before its bight has been carried through two right angles of angular movement, and means for slidably detaining one strand of each loop near the path of descent of the needle while the loop is being drawn out between the said sliding surfaces.

7. In a sewing machine, the combination of a rotatable disk, a stationary casing in slidable contact with one face of the disk, a circular tongue on the face of the disk co-operating with an arcuate groove in the adjacent face of the casing to draw out successive loops from the needle thread but allow each loop to be released before its bight has been carried through two right angles of angular movement, a part of the tongue being removed to present an abutment to engage the bulging strand of the needle thread as the needle begins to ascend.

8. In a sewing machine, the combination with angularly movable means for engaging the needle thread, of a stationary casing laterally situated with respect to the plane of movement of the aforesaid means and in slidable contact therewith, the adjacent faces coöperating to draw out successive loops from the needle thread but allow each loop to be released before its bight has been carried through two right angles of angular movement, and means for keeping the stationary casing in its lateral position with respect to the loop-drawing means but per-

- mitting the loops of thread to pass over the casing.
9. In a sewing machine, the combination with angularly movable means for engaging the needle thread, of a stationary casing laterally situated with respect to the plane of movement of the aforesaid means and in slidable contact therewith, the adjacent faces coöperating to draw out successive loops from the needle thread but allow each loop to be released before its bight has been carried through two right angles of angular movement, means for retaining the stationary casing in its lateral position with respect to the loop-drawing means but permitting the loops of thread to pass over the casing, and means for operating the said retaining means synchronously with the loop-drawing means.
10. In a sewing machine, the combination with an angularly movable loop-drawing device operating to draw out successive loops from the needle thread but allow each loop to be released before its bight has been carried through two right angles of angular movement, and a stationary casing around and over which the loops pass, of a rotatable member in contact with the casing to keep it in position relatively to the loop-drawing device.
11. In a sewing machine, the combination with an angularly movable loop-drawing device, of a stationary casing situated laterally with respect to one face of the loop drawing device, coöperating parts upon the adjacent faces of the device and the casing to entrap the needle thread and draw out a loop between the adjacent faces before it has been carried through two right angles of angular movement, an angularly movable member for retaining the stationary casing in its lateral position with respect to the loop-drawing device, and means for operating the angularly movable member so that the travel of a gap in its surface synchronizes with the travel of the loops of thread in being drawn up around the casing.
12. In a sewing machine, the combination with an angularly movable loop-drawing device, of a stationary casing situated laterally with respect to one face of the loop drawing device, coöperating parts upon the adjacent faces of the device and the casing to entrap the needle thread and draw out a loop of needle thread between the adjacent faces and deliver the bight of the loop at the tail of the casing before the bight has been carried through two right angles of angular movement, and a rotatory member mounted in contact with the outer face of the casing to keep it in its lateral position relatively to the loop drawing device.
13. In a sewing machine, the combination with an angularly movable loop drawing de-
- vice, operating to draw out successive loops from the needle thread but allow each loop to be released before its bight has been carried through two right angles of angular movement, of a stationary casing laterally situated with respect to one face of the loop-drawing device, and an angularly movable loop arresting and retaining element in the said casing.
14. In a sewing machine, the combination with an angularly movable loop-drawing device operating to draw out successive loops from the needle thread but allow each loop to be released before its bight has been carried through two right angles of angular movement, of a stationary casing laterally situated with respect to one face of the loop drawing device, an angularly movable loop arresting and retaining element in the said casing, and means for exerting a yielding restraint to the angular movement of the said element as the sewing advances.
15. In a sewing machine, the combination with an angularly movable loop drawing device operating to draw out successive loops from the needle thread but allow each loop to be released before its bight has been carried through two right angles of angular movement, of a tension device comprising a stationary casing, laterally situated with respect to one face of the loop drawing device, an angularly movable loop arresting element within said casing, means whereby the said element is locked during the arresting of a loop, means whereby it is then unlocked, and means whereby it then yieldingly retains the loop until one or more stitches are completed and the bight has been penetrated by the needle.
16. In a sewing machine, the combination with an angularly movable loop drawing device, operating to draw out successive loops from the needle thread but allow each loop to be released before its bight has been carried through two right angles of angular movement, of a tension device comprising a stationary casing laterally situated with respect to one face of the loop drawing device, a loop arresting and retaining element mounted within the casing, and means operating to temporarily deprive the loop arresting and retaining element of its loop arresting property after arresting a loop and then to temporarily deprive it of its loop retaining property also.
17. In a sewing machine, the combination with an angularly movable loop drawing device, operating to draw out successive loops from the needle thread but allow each loop to be released before its bight has been carried through two right angles of angular movement, of a tension device comprising a stationary casing laterally situated with respect to one face of the loop drawing device,

a loop arresting and retaining element mounted within the casing, and serving to engage, retain, protect and release a loop in sequence, and means operating to restore the 5 said element to its original position after the loop has been released.

18. In a sewing machine, the combination with a reciprocating needle, of an angularly movable loop drawing device, operating to 10 draw out successive loops from the needle thread but allow each loop to be released before its bight has been carried through two right angles of angular movement, and a tension device comprising a casing around 15 which the loops pass, a loop arresting and retaining element rotatably mounted within said casing, and means for centralizing the loop so as to be in position for penetration by the needle.

19. In a sewing machine, the combination with a reciprocating needle, of an angularly movable loop drawing device, operating to draw out successive loops from the needle 20 thread but allow each loop to be released before its bight has been carried through two right angles of angular movement, and a tension device comprising a casing around 25 which the loops pass, a loop arresting and retaining element rotatably mounted within said casing, and a movable horn which accompanies the loop retaining element during part of its travel, and centralizes the loop so as to be in position for penetration by the needle.

20. In a sewing machine, the combination with an angularly movable loop drawing device operating to draw out successive loops from the needle thread but allow each loop to be released before its bight has been carried 30 through two right angles of angular movement, of a tension device comprising a casing around which the loops pass, a loop arresting and retaining element rotatably mounted within 35 said casing, and a movable horn which accompanies the loop retaining element during part of its travel, and centralizes the loop so as to be in position for penetration by the needle.

21. In a sewing machine, the combination with an angularly movable loop drawing device, operating to draw out successive loops from the needle thread but allow each loop to be released before its bight has been carried 40 through two right angles of angular movement, of a tension device comprising a casing and a loop arresting and retaining element therein, said element comprising two relatively movable members one of 45 which shrouds the other when a loop has been arrested.

22. In a sewing machine, the combination with an angularly movable loop drawing device, operating to draw out successive loops from the needle thread but allow each loop to be released before its bight has been carried 50 through two right angles of angular movement, of a tension device comprising a casing and a loop arresting and retaining element in the form of two relatively movable members, a loop-arresting finger on one member, a finger-shrouding arm on the other member, means whereby the shrouding arm tends always to shroud the finger, 55 and means whereby the said finger is exposed at proper intervals to enable it to perform its loop arresting and its loop releasing functions.

23. In a sewing machine, the combination with an angularly movable loop drawing device, operating to draw out successive loops from the needle thread but allow each loop to be released before its bight has been carried 60 through two right angles of angular movement, of a tension device comprising a casing and a loop arresting and retaining element in the form of two relatively movable members, a loop-arresting finger on one member, a finger-shrouding arm on the other member, means whereby the shrouding arm tends always to shroud the finger, 65 and means whereby the said finger is exposed at proper intervals to enable it to perform its loop arresting and its loop releasing functions.

vice, operating to draw out successive loops from the needle thread but allow each loop to be released before its bight has been carried through two right angles of angular movement, of a tension device comprising a casing and a loop arresting and retaining element in the form of two relatively movable members, a loop-arresting finger on one member, a finger-shrouding arm on the other member, means whereby the shrouding arm tends always to shroud the finger, 70 means for locking the finger-carrying member in suitable positions and moving the member carrying the shrouding arm into an unshrouding position, means whereby the last mentioned means are operated, and means whereby the locking and unshrouding of the respective members is again effected when the loop arresting and retaining element as a whole has, by yielding to the pull of the loop, reached a position in which the finger is close to the needle hole in the needle plate.

24. In a sewing machine, the combination with an angularly movable loop drawing device, operating to draw out successive loops from the needle thread but allow each loop to be released before its bight has been carried through two right angles of angular movement, of a tension device comprising a casing and a loop arresting and retaining element in the form of two relatively movable members, a loop-arresting finger on one member, a finger-shrouding arm on the other member, means whereby the shrouding arm tends always to shroud the finger, 90 a single member capable, when operated at proper intervals, of locking the finger-carrying member and of moving the member carrying the shrouding arm into its unshrouding position, and means for operating the said single member.

25. In a sewing machine, the combination with an angularly movable loop drawing device, of a stationary tension device situated laterally with respect to one face of the loop-drawing device, the adjacent faces co-operating to draw out successive loops from the needle thread but allow each loop to be released before its bight has been carried 100 through two right angles of angular movement, the said tension device comprising a casing and a loop arresting and retaining element in the form of two relatively movable members one of which shrouds the other when a loop has been arrested.

26. In a sewing machine, the combination with an angularly movable loop drawing device, of a stationary tension device situated laterally with respect to one face of the loop drawing device, the adjacent faces co-operating to draw out successive loops from the needle thread but allow each loop to be released before its bight has been carried 110 through two right angles of angular movement, the said tension device comprising a casing and a loop arresting and retaining element in the form of two relatively movable members one of which shrouds the other when a loop has been arrested.

ment, the said tension device comprising a casing, a loop arresting and retaining element in the form of two relatively movable members, a loop arresting finger on one member, a finger shrouding arm on the other member, means whereby the shrouding arm tends always to shroud the finger, and means whereby the said arm is moved into an unshrouding position to enable the said finger 10 to perform its loop arresting and loop releasing functions.

26. In a sewing machine, the combination of an angularly movable disk, a stationary tension device located laterally with respect 15 to one face of said disk, a segmental flange on the disk and a groove on the tension device coöperating to engage the needle thread, draw out the bight of a loop between the disk and tension device and release the loop in a position free to be drawn 20 up around the tension device.

27. In a sewing machine, the combination of a rotary disk, and a stationary casing located laterally with respect to one face of 25 said disk, a flange on said disk and a slot in the adjacent face of the casing coöperating to engage the needle thread, draw out the bight of a loop between them, and release the loop in a position free to be drawn up 30 around the casing.

28. In a sewing machine, the combination of a rotary disk, a stationary tension device located laterally with respect to one face of

said disk, and means whereby loops of needle thread are engaged, drawn out between the 35 adjacent lateral faces of the disk and casing and released within one hundred and twenty degrees of angular movement of the disk, the point of release being such that the loops can be drawn up around the stationary casing, and means for arresting certain of the 40 needle loops.

29. In a sewing machine, the combination of a rotary member and a laterally situated 45 stationary casing each having means on their adjacent lateral faces coöperating with one another to engage the needle thread, draw out a loop, and release it in a position whence it can be drawn up around the casing.

30. In a sewing machine, the combination of a rotary disk a stationary tension device situated laterally with respect to one face of 50 said disk, the disk and tension device each having means on their adjacent faces which coöperate to engage the needle thread, draw out a loop and release the same within one hundred and twenty degrees of movement 55 of the disk.

In testimony whereof I affix my signature 60 in presence of two witnesses.

FREDERICK BAKER.
